UNITED STATES PATENT OFFICE.

JAMES POTTER, OF CHICAGO, ILLINOIS.

UNIVERSAL LUBRICATOR.

SPECIFICATION forming part of Letters Patent No. 293,781, dated February 19, 1884.

Application filed August 2, 1883. (No model.)

To all whom it may concern:

Be it known that I, JAMES POTTER, a citizen of the United States, residing at Chicago, in the county of Cook and State of Illinois, 5 have invented a new and useful Improvement in Universal Lubricators; and I do hereby declare the following to be full, clear, and exact description of the invention, reference being had to the accompanying drawings, and figures of reference marked thereon, which form a part of this specification.

In order to fully understand the different parts of my device, I have designated the sides of the receiver, the front and back sides, and 15 right and left ends.

Figure 1 is a sectional view of the part that forms a portion of the reservoir and walls of the receiver; Fig. 2, perspective view of one of the end walls of the receiver; Fig. 3, perspective view of Figs. 1 and 2 united; Fig. 4, perspective view of the reverse side of Fig. 3; Fig. 5, vertical view of blank used to form guideway for the feed-slide; Fig. 6, plan of the cover for back wall of receiver. Fig. 7 shows the screw-cap used. Fig. 8 represents the right-end elevation. Fig. 9 shows the left-end elevation; Fig. 10, plan of the front of my lubricator; Fig. 11, plan of the back of my lubricator. Fig. 12 is a central sectional elevation 30 of the lower part of my device with wick removed, the walls and flanges of the receiver in heavy lines; Fig. 13, also a central sectional elevation, showing the position of the various parts when brought in action; Figs. 14 and 15, plan of the clamps for holding the wick; Fig. 16, plan of the wick-conductor and protection-loop; Fig. 17, central sectional elevation of the same; Fig. 18, plan of the clamps for holding the rod G; Fig. 19, sectional view of the same.

40 The object of my present invention is an improvement on my patent of June 12, 1883, No. 279,181, in the manner of construction and in the feeding of the wick outward as fast as used up, and in the regulating of the flow of the lubricating compound, so that I can use other classes of compounds or liquids than those mentioned at that date, and so devote my device to other uses. The reservoir A is made hollow and fashioned flat one way and cylind-

rical the other, the flat parts extending down 50 and forming the end walls of the receiver B, Fig. 2. From the cylindrical sides I also extend downward the piece of material that forms that part from the point A', to make the front and back walls of the receiver. I unite the 55 said parts by soldering the surface of the cylindrical parts to an L-flange, B', formed on the outer edges of the flat parts, by which means I avoid bringing the raw edges of the material together and make a closer joint. 60

On one side of the reservoir A, Fig. 3, is an opening, b, through which the lubricant is inserted and afterward covered by the screw-cap C, Fig. 7.

Upon the right and left end walls of the receiver B, soldered thereto, at a and a', are the blanks B², on the outside edges of which I turn an L-flange, B³, which stand inward when mitered to the said walls, Fig. 5.

Extending across the front surface of the receiver, Fig. 10, detainably held by the flanges B³ on either side, is the feed-slide D, constructed and so arranged as to be about four-fifths the length of the front wall of the receiver. Soldered upon the under side of said slide are the teeth D', set so their points incline toward the lower end of the slide, and are the means of detaining the wick in place, and also feed the same out as fast as worn off. The movement of the slide is indicated by the dotted lines in Figs. 12 and 13, the curved shoulders e in the flange B³ forming the guideway for the downward and forward movement, and the shoulders d the stop, to prevent the slide from moving back while holding the wick. In Fig. 13 the slide is represented in the latter position. The springs E assist and hold up the slide in its vertical adjustment and withdrawal from the wick to obtain a new hold, the upper ends of which are soldered at 90 A' to the front wall of the receiver, and have a bearing against the slide at their lower ends. Upon the outside surface of the slide is fastened the thumb-piece D², the pressing down of which, with the assistance of the springs E, 95 causes the movements previously referred to. The teeth D', in operating the wick, enter slots e, Fig. 3, cut into the receiver, which are a

little wider than the thickness of the teeth, and long enough to allow free action thereof.

Securely fastened upon the opposite side or back wall of the receiver B are the springs F, that form part of the mechanism for controlling the flow of the lubricant.

Stretching across and above these springs is the rod G, passing from one end of the blanks B³ to the other, and projecting beyond the same on either end.

Upon one end is the thumb-piece f, by which the rod is revolved. Placed at a certain distance from each end of the receiver upon said rod are the cams H, which rest against the springs F.

The rod G is held in the center 15 by the clamps I, whose flanges I' rest upon the back wall of the receiver. The whole operate to retain the rod and the cams in the desired positions in regulating the flow of the lubricant.

The screw J is intended to tighten 20 on the clamps I on the rod G when in the working of said rod the friction has worn the clamping part away.

The device for holding the wick is composed of one piece of tin or other material 25 bent at the upper end so as to form two parallel pieces or clamps, L and L', which embrace the wick on either side and introduce it into the receiver.

In the clamp L, Fig. 15, at the lower end, 30 are cut slots g, corresponding in size, width, and length with the slots e in the receiver, through which the teeth D' reach in working out and holding the wick.

To the clamp L', Fig. 13, on the inner side, 35 is fastened the interior lip or jaw, L², so arranged that it is the same width as the said clamp and about a third as long. The lip L² is soldered at its upper end to the clamp L' in such a way as leaves the lower end free 40 to work back and forth, as regulated by the springs F.

Into the clamp L', at the lower end, are cut holes h, which correspond with the slots i, Fig. 4, and form openings for action of the 45 springs F.

The operation of the entire mechanism for controlling the flow of the lubricant is as follows: The turning of the rod G by the thumb-piece f revolves the cams H, which 50 force the springs F against the lip L² through the openings h and i, causing the said lip to squeeze the wick at its lower end, and so control the flow of the lubricant. The movements of the rod and springs F are covered 55 by the cover K, which is soldered to the flanges B³ on either side, and extends from the point A' to the lower end of the receiver-wall. The slots K' help to retain the cams H in their places, and from moving sidewise 60 if the rod G becomes loose by accident or otherwise. The points H prevent the turning of the cams too far around by striking the surface of the cover K. The openings j in the clamps L are intended to aid the lubricant to more readily saturate the wick. The 65 projection or indenture k on the lower edge of

the back wall of the receiver, Fig. 12, prevents the clamps from leaving the receiver when the slide D is feeding out the wick, said indenture entering the hole L' when the clamps are introduced within the walls of the receiver.

To more readily take the clamps L from the receiver, to insert a new wick and cleanse the parts to introduce different lubricating compounds, I form a flange, L', on the clamp 70 L', Fig. 14, the pressing in of which with the thumb relieves the clamps from the indenture k, and so permits the withdrawal. The opening l in the cover K is intended to give room for the thumb while withdrawing the 80 clamps.

M denotes the wick-conductor, composed of lamp-wick doubled up as many times as is necessary to entirely fill up the space between the clamps L and L', so when the clamps 85 are inserted into the receiver the outside surface of the clamps will fit snugly the lower ends of the walls of said receiver and prevent any flow of the lubricant outside of the clamps. At the upper end of the wick I securely fasten a protection-loop, O, so constructed as to have on each end a curved point, O', that stands away from the wick, whose object is to prevent the wick from coming entirely out of the clamps when nearly 95 used up by striking against the indenture L' on the clamp L, Figs. 15 and 17, which is turned inward from the lower edge of said clamp, and of the same description as the indenture k.

N represents the handle to hold my device with, formed of wood or other substance, and inserted in the cap N', which is of the same material as the lubricator, and soldered on the back wall of the receiver.

While I can still use my lubricator for the purposes spoken of in my last patent, my design in the present invention is to provide a lubricator in which I can employ oil, turpentine, or any other class of liquids, and so 110 devote my device to many uses—such as the oiling of a circular saw while in motion—the oiling and staining of woods and furniture, the oiling of machinery and fine castings to prevent rust, and many other articles 115 of use where only a little lubricant is desired.

What I claim, and desire to secure by Letters Patent of the United States, is—

1. In a lubricator, the combination of the reservoir A, the receiver B, the blanks B², provided with flanges B³, and shoulders e and d, the feed-slide D, and teeth D', the thumb-piece D², the springs E with a wick, M, the whole operated as described and set forth.

2. In a lubricator, the combination of the reservoir A, the receiver B, the blanks B², provided with flanges B³, the springs F, the rod G, the thumb-piece f, the cams H, the points H', the clamps I, provided with screw J, the cover K, and openings K', with clamps L and L', provided with lip L², and wick M, all for the purpose described and set forth.

3. In a lubricator, the reservoir A, the receiver B, the handle N, the cap N', the indenture k, in combination with clamps L and L', the flange L³, the openings L⁴, and wick 5 M, the whole operating as described and set forth.

4. In a lubricator, the wick M, provided

with loop O, the points O', in combination with clamps L and L', and the indenture L⁵, all for the purpose described and set forth.

JAMES POTTER.
